UNITED STATES PATENT OFFICE.

WALLACE DOUMA AND JAMES DOUMA, OF GRAND RAPIDS, MICHIGAN.

SAW GAUGE.

Application filed February 20, 1923. Serial No. 620,299.

To all whom it may concern:

Be it known that we, WALLACE DOUMA and JAMES DOUMA, citizens of the United States, residing at Grand Rapids, in the county of Kent and State of Michigan, have invented certain new and useful Improvements in Saw Gauges, of which the following is a specification.

The primary object of our invention is 10 the provision of such an article that is well adapted for attachment to saws of the straight-edge type for cooperating therewith to provide a square, beveled square, or liquid-level gauge.

15 Our invention is also well adapted to be employed in conjunction with a straight-edge strip of metal whenever a straight-edge saw is not available, the article being additionally characterized by its simplicity of 20 construction and ease of application to conventional types of saws.

The nature and advantages of the invention will be better understood when the following detailed description is read in connection with the accompanying drawings, 25 the invention residing in the construction, combination, and arrangement of parts as claimed.

In the drawings forming part of this application, like characters of reference indicate similar parts in the several views, and wherein:—

Figure 1 is an elevational view of one end 35 of a conventional type of saw, our attachment being shown in position thereon, and certain of the elements thereof being shown in full and dotted line positions;

Fig. 2 is a vertical sectional view taken substantially upon the line 2—2 of Fig. 1;

Fig. 3 is a transverse cross-sectional view 40 upon the line 3—3 of the same figure; and

Fig. 4 is a perspective view of a metallic strip that may be employed in conjunction 45 with our invention in lieu of a straight-edge saw.

Referring to the drawings in detail, there is shown a saw of conventional type constituting the usual blade 6 and handle 6'. It is necessary however, that our device be 50 employed with a saw of a character wherein the handle thereof has vertical edges *a* at opposite sides of the saw blade as well as beveled or obliquely inclined edges *b* at the upper end of the handle and being a continuation of said vertical edges.

Our attachment includes a centrally split

metallic strip or arm 7 adapted for straddling said blade 6 and detachably secured thereto adjacent its upper end. The inner edge of this strip or arm 7 is in close contact with the vertical edges *a* of the saw handle 6', and the upper end of said arm is formed with a rearwardly inclined portion 7', the inner edge of which also has close contact with the beveled edges *b* of 65 the said saw handle.

The securing means between the arm and saw blade may be and preferably is in the form of a bolt 8, screw-threaded at one end and formed with a thumb-nut 9 at its opposite end. This bolt engages through alined openings in opposite sides of the arm 7 as well as an opening in said blade 6. The opening in the arm 7 upon one side of the split portion is screw-threaded for 75 the reception of the screw-threaded end of said bolt 8.

Also straddling the saw blade 6, and adjustably connected to the rearwardly inclined portion 7' of the arm 7 is a split 80 liquid level 10. This level is provided adjacent its upper end with a relatively long slot 11 through which is extended a pin 12, the opposite ends thereof being headed as at 13, and adapted for securing the upper 85 ends of a pair of links 14 to the said level 10. The opposite ends of these links are slotted at 15 and projecting therethrough are the opposite ends of a headed bolt 16. Inwardly of the headed end of this bolt, the 90 same is formed with a square portion 17, which fits within the slot of the adjacent link for preventing the turning of the said bolt. The link 14 is connected with the level 10 at a point above the straight edge of the 95 blade 6.

The opposite end of this bolt is screw-threaded for receiving a wing-nut 18, which nut will effectively bind the links upon opposite sides of the rearwardly inclined portion 7' of the arm 7 for maintaining the level 10 in adjusted positions with respect to said arm. When our device is employed in conjunction with a saw, and the level 10 is in a position as shown by the full lines of Fig. 1, there is provided a complete beveled square. When this level 10 is in a vertical position as per the dotted lines of this figure, it will be seen that there is provided a square gauge.

It is of course, to be understood that our attachment in no way interferes with the proper manipulation of the saw itself, it

being noted that by releasing the wing-nut 18, the level 10 may be extended upwardly away from the teeth of the saw blade.

However, at any time, if a saw should not 5 be available, and it is desired to use our device, we have provided a metallic strip 19 (Fig. 4), having an opening 20 therein and adjacent one of its ends. This strip is 10 adapted to be secured to the arm 7 through the instrumentality of the bolt 8 and extends at right angles to the arm, and will effectively substitute for the straight edge of the saw blade.

If the gauge 7 is not employed upon a 15 saw blade 6 as illustrated in Fig. 1, the blade 19, as shown in Fig. 4, is used. The structure shown in Fig. 1 involves a handle applied to the blade, and which is lacking upon the blade 19. The handle of the 20 saw is used as a means for effecting the quick and accurate adjustment of the gauge. This handle might be dispensed with, but of course it would require the exercise of some 25 judgment to assemble the gauge 7 accurately upon the blade 19, as shown in Fig. 4. When the gauge is once positioned thereon and accurately disposed, it may be used as conveniently and effectually as though it were mounted upon a saw blade.

Although we have herein shown and described the preferred embodiment of the present invention, it is nevertheless to be understood that minor changes may be made 30 therein, without departing from the spirit and scope of the invention as claimed.

Having described the invention, what is claimed is:—

1. In combination with a blade having a straight edge, a handle applied to the 40 blade and provided with a straight edge disposed at a right angle to the straight

edge of the blade, said handle also having a straight edge which is disposed at an acute angle to both of the before-mentioned straight edges, a split arm adapted 45 to straddle the blade and having end portions which bear against both of the straight edges of the handle, one edge of the arm when so applied being disposed at a right angle to the straight edge of the blade, a liquid level adapted to be disposed along the side of the blade, and a link connecting the level with the arm at a point 50 above the straight edge of the blade, and means for securing the level at a fixed position with relation to the arm and the blade whereby the level may be disposed along the straight edge of the arm or along the edge of the obliquely disposed portions of the arm 55 with which the said level is connected. 60

2. In combination with a blade having a straight edge, an arm adapted to be secured thereto and having a straight edge adapted to be disposed at a right angle to the straight edge of the blade, said arm having obliquely disposed end portions, a liquid level adapted to be disposed transversely of the blade, a link connecting the level with the arm at a point above the straight edge 65 of the blade, means for securing the level at a fixed position with relation to the blade and the arm whereby the level may be disposed with one of its edges at a right angle to the straight edge of the blade or in a line 70 parallel with the edge of that obliquely disposed end portion of the arm to which the level is connected. 75

In testimony whereof we affix our signatures.

JAMES DOUMA.
WALLACE DOUMA.
